UNITED STATES PATENT OFFICE.

LEWIS H. BULLARD, OF KALAMAZOO, MICHIGAN.

SOFA-BED OR BED-COUCH.

SPECIFICATION forming part of Letters Patent No. 763,958, dated July 5, 1904.

Application filed November 2, 1903. Serial No. 179,559. (No model.)

To all whom it may concern:

Be it known that I, LEWIS H. BULLARD, a citizen of the United States, residing at the city of Kalamazoo, in the county of Kalamazoo and 5 State of Michigan, have invented certain new and useful Improvements in Sofa-Beds or Bed-Couches, of which the following is a specification.

This invention relates to improvements in 10 sofa-beds or bed-couches.

The objects of this invention are, first, to provide an improved sofa-bed or bed-couch which is comparatively light in weight and attractive in finish and appearance when adjusted either as a bed or as a couch or sofa; second, to provide an improved bed-couch or sofa-bed which may be quickly and easily adjusted and is stable in both its adjusted positions; third, to provide, in a sofa-bed or bed-couch, improved connections for the adjusting parts; fourth, to provide an improved bed-couch which is simple in structure, economical to produce, and durable in use.

Further objects and objects relating to 25 structural details will definitely appear from the detailed description to follow.

I accomplish the objects of my invention by the devices and means described in the following specification.

30 The invention is clearly defined and pointed out in the claims.

A structure embodying the features of my invention is clearly illustrated in the accompanying drawings, forming a part of this specification, in which—

Figure 1 is an end elevational view of my improved sofa-bed or bed-couch adjusted as a sofa or couch. Fig. 2 is an end elevational view of my improved sofa-bed or bed-couch 40 adjusted as a bed. Fig. 3 is a rear elevational view of my improved sofa-bed adjusted as a sofa. Fig. 4 is an enlarged detail sectional view of the hinge connection of the front and rear bottom sections of my improved sofa-bed, 45 taken on a line corresponding to line 4-4 of Fig. 3, the relation of the parts when adjusted as a bed being indicated by dotted lines. Fig. 5 is a detail view similar to Fig. 4 of a modified construction, showing a cam-block 50

B'' as a rest for the rear section B' when adjusted as a sofa. Fig. 6 is an enlarged detail sectional view taken on line 6-6 of Fig. 1, the relation of the parts when adjusted as a bed being indicated by dotted lines. Fig. 7 is an enlarged detail sectional view taken on line 7-7 of Fig. 1. Fig. 8 is an enlarged detail elevational view of the supporting means for the rear section when adjusted as a bed. Fig. 9 is an enlarged detail sectional view taken on a line corresponding to line 9-9 of Figs. 2 and 60 8. Fig. 10 is an enlarged detail sectional view taken on a line corresponding to line 10-10 of Fig. 11 of the hinge connection for the top-rail sections. Fig. 11 is a detail sectional view taken on line 11-11 of Fig. 10. 65

In the drawings all of the sectional views are taken looking in the direction of the little arrows at the ends of the section-lines, and similar letters of reference refer to similar parts throughout the several views. 70

Referring to the drawings, the end portions of my improved bed-couch are formed of front sections A A and rear sections A' A'. These sections are secured together, by means which will be hereinafter fully described, so that the 75 rear sections may be folded substantially at right angles to the front sections when the structure is adjusted as a couch. The top rails of the end portions consist of sections a a', which are continued down to form the legs O 80 and O', as is usual in iron-frame bedsteads. The sections are made up of the top-rail sections a and bottom cross-rails d, connected by suitable spindles or by any suitable or desired 85 ornamental work. The rear sections are made up of the top-rail section a' and the bottom cross-rails d', connected by suitable spindles or ornamental work to correspond to that of the front section. The front section is provided with rear legs O'', as clearly appears in 90 Figs. 1, 2, and 3 of the drawings. The top-rail sections a a' are of the same size, so as to form in appearance one continuous rail when adjusted as a bed. (See Fig. 2.) The hinge 95 connections for these sections will be herein-after described. The front section is provided with side rails D D, which are secured in position in the usual or any desired manner.

The bottom of my improved folding bed consists of a front section B and a rear section B'. The sections B B' are provided with supports b b'. The outer supports b b' are 5 adapted to rest upon the side rails of the bed-sections A A'. The rear section B' is secured to the front section B by hinges F, carried on the rear rail D of the front section A. Slides F' are secured to the free leaves of the hinges 10 F. These slides are adapted to receive the ends of the cross-pieces f, which are secured to the longitudinal strips b' and to the side rail C of the rear bottom section. (See Figs. 3, 4, and 6.) Links e, having slots e' therein 15 which engage suitable studs on the rear section B', are pivotally secured to the front section B. (See Fig. 4.) These links are of a suitable length so that when the sections B B' are in their open position they are held abutted 20 against each other. These links are slotted to permit of the adjustment of the rear section, which is carried upward and forward onto the front section in folding, as clearly appears in Fig. 4, where the same is shown in such position, its open position being indicated by 25 dotted lines. In the modified construction shown in Fig. 5 the end pieces of the rear section B' rest upon the cam-blocks B'' on the front section, which as it is pushed forward 30 elevates the same gradually. The rear bottom section being carried upward and forward in folding permits of the folding of the end sections A' behind the same at substantially right angles to the sections A. (See Figs. 1 and 3.)

35 The rearwardly-projecting arms d'' of the rails d are provided with upwardly-projecting pivot-pins g. The inner ends of the bottom rails d' of the rear section are slotted at g' to engage these pins and rest upon the extensions or arms. Links e are pivoted to the arms d''. These links are slotted at e' to engage suitable projecting pins on the rails d'. Cams h are provided on the outer ends of the arms d''. Pins h', carried by the rails d', 40 bear against these cams and as the sections are swung inward lift or tilt the same, so that the legs O' are raised from the floor. The cams h are notched at h'' to receive the pins h', so that as the rear sections are carried 45 rearwardly the pins h' drop into the notches and lock the sections in their closed position. The section B' is detachably secured to the cross-piece f by the turn-button f' carried thereby. When it is desired to open the sections, they are raised slightly until the pins 50 are disengaged from the notches, when they are free to swing back into their open positions.

The top-rail sections a a' are pivotally secured together by means of the blocks j, arranged in the sections a. These blocks are provided with projecting tongues with slots j'' therein. These tongues are arranged in the ends of the section a', and a pin j' engages

the slots j'', which permit a slight longitudinal motion of the parts in relation to each other to allow the swinging and tilting of the rear sections. With the sections thus secured together they are readily adjusted and when adjusted have the appearance of being a continuous structure, as appears in Fig. 2, the hinge connection being practically obscured. As before stated, as the rear sections are swung inward the rear legs O' are raised by means of the cam h and the pin h' riding 75 thereon, so that the legs are free from the floor in swinging and when in the inner position, as appears in Figs. 1 and 3, so that they are much more easily adjusted and do not wear upon the floor and also the structure may be readily moved about when adjusted as a couch.

Secured to the legs O' of the rear sections A' are brackets i i', which are provided with upwardly-projecting pins i''. The side rails 85 C are adapted to rest on these brackets and are perforated at the ends to engage the pins i'' when the structure is in its open position. (See Figs. 8 and 9.)

As before stated, when the rear bottom section B is folded the same is carried upwardly and forwardly, so that the bedding is held in proper position and proper allowance is made therefor.

My improved bed-couch is comparatively 95 light in weight and is attractive in appearance. The same is also very easy to adjust and when adjusted in either position can be readily moved about.

The structure as illustrated and described 100 is the form preferred by me on account of its simplicity, durability, and economy in manufacture. I am, however, aware that it is capable of very considerable variation in structural details without departing from my invention.

Having thus described my invention, what I claim as new, and desire to secure by Letters Patent, is—

1. In a structure of the class described, the combination of the end sections A A and A' A'; abutting top rails a and a' therefor; slotted tongues j projecting from said rails a into said rails a'; suitable pivot-pins j' engaging said slots; bottom cross rails or pieces d'' for said sections A'; rearwardly-projecting arms d'' on said sections A; upwardly-projecting pins g on said arms d''; slots g' in said cross-pieces d'' engaging said pins; cams h on said arms d'' having notches h'' therein; pins h' on said cross-pieces d'' adapted to rest against said cams; a link e pivotally secured to said arms d'' having slots e' therein; suitable pins on said cross-pieces d'' engaging said slots e'; side rails D for said sections A; a bottom consisting of a front section B and a rear section B'; hinges F secured to the rear side rail D; cross-pieces f for said rear bottom section,

slidably secured to the free leaves of said hinges; links *c* having slots *c'* therein, pivotally secured to said section B; and pins on said section B' arranged through said slots, 5 all coacting for the purpose specified.

2. In a structure of the class described, the combination of the end sections A A and A' A'; abutting top rails *a* and *a'* therefor; slotted tongues *j* projecting from said rail *a* into said rails *a'*; suitable pivot-pins *j'* engaging said slots; bottom cross rails or pieces *d'* for said sections A'; rearwardly-projecting arms *d''* on said sections A; upwardly-projecting pins *g* on said arms *d''*; slots *g'* in said cross-pieces 15 *d'* engaging said pins; a link *e* pivotally secured to said arms *d''* having slots *e'* therein; suitable pins on said cross-pieces *d'* engaging said slots *e'*; side rails D for said sections A; a bottom consisting of a front section B and 20 a rear section B'; hinges F secured to the rear side rail D; cross-pieces *f* for said rear bottom section, slidably secured to the free leaves of said hinges; links *c* having slots *c'* therein, pivotally secured to said section B; and pins 25 on said section B' arranged through said slots, all coacting for the purpose specified.

3. In a structure of the class described, the combination of the end sections A A and A' A'; abutting top rails *a* and *a'* therefor; slotted 30 tongues *j* projecting from said rails *a* into said rails *a'*; suitable pivot-pins *j'* engaging said slots; bottom cross rails or pieces *d'* for said sections A'; rearwardly-projecting arms *d''* on said sections A; upwardly-projecting pins 35 *g* on said arms *d''*; slots *g'* in said cross-pieces *d'* engaging said pins; cams *h* on said arms *d''* having notches *h'* therein; pins *h'* on said cross-pieces *d'* adapted to rest against said cams; side rails D for said sections A; a bottom 40 consisting of a front section B and a rear section B'; hinges F secured to the rear side rail D; cross-pieces *f* for said rear bottom section, slidably secured to the free leaves of said hinges; all coacting for the purpose specified.

4. In a structure of the class described, the combination of the end sections A A and A' A'; 50 abutting top rails *a* and *a'* therefor; slotted tongues *j* projecting from said rail *a* into said rails *a'*; suitable pivot-pins *j'* engaging said slots; bottom cross rails or pieces *d'* for said sections A'; rearwardly-projecting arms *d''* on 55 said sections A; upwardly-projecting pins *g* on said arms *d''*; slots *g'* in said cross-pieces *d'* engaging said pins; side rails D for said sections A; a bottom consisting of a front section B and a rear section B'; hinges F secured to the 60 rear side rail D; cross-pieces *f* for said rear bottom section, slidably secured to the free leaves of said hinges; all coacting for the purpose specified.

said slots, all coacting for the purpose specified. 65

5. In a structure of the class described, the combination of the end sections A A and A' A'; abutting top rails *a* and *a'* therefor; slotted tongues *j* projecting from said rail *a* into said rails *a'*; suitable pivot-pins *j'* engaging said slots; bottom cross rails or pieces *d'* for said sections A'; rearwardly-projecting arms *d''* on 70 said sections A; upwardly-projecting pins *g* on said arms *d''*; slots *g'* in said cross-pieces *d'* engaging said pins; cams *h* on said arms *d''* having notches *h''* therein; pins *h'* on said cross-pieces *d'* adapted to rest against said cams; a link *e* pivotally secured to said arms *d''* having slots *e'* therein; suitable pins on 75 said cross-pieces *d'* engaging said slots *e'*; side rails D for said sections A; a bottom consisting of a front section B and a rear section B'; hinges F secured to the rear side rail D; cross-pieces *f* for said rear bottom section, slidably secured to the free leaves of said hinges; all coacting for the purpose specified. 80

6. In a structure of the class described, the combination of the end sections A A and A' A'; abutting top rails *a* and *a'* therefor; slotted 90 tongues *j* projecting from said rail *a* into said rails *a'*; suitable pivot-pins *j'* engaging said slots; bottom cross rails or pieces *d'* for said sections A'; rearwardly-projecting arms *d''* on said sections A; upwardly-projecting pins *g* 95 on said arms *d''*; slots *g'* in said cross-pieces *d'* engaging said pins; a link *e* pivotally secured to said arms *d''* having slots *e'* therein; suitable pins on said cross-pieces *d'* engaging said slots *e'*; side rails D for said sections A; a bottom 100 consisting of a front section B and a rear section B'; hinges F secured to the rear side rail D; cross-pieces *f* for said rear bottom section, slidably secured to the free leaves of said hinges; all coacting for the purpose specified. 105

7. In a structure of the class described, the combination of the end sections A A and A' A'; abutting top rails *a* and *a'* therefor; slotted 110 tongues *j* projecting from said rails *a* into said rails *a'*; suitable pivot-pins *j'* engaging said slots; bottom cross rails or pieces *d'* for said sections A'; rearwardly-projecting arms *d''* on said sections A; upwardly-projecting pins *g* 115 on said arms *d''*; slots *g'* in said cross-pieces *d'* engaging said pins; cams *h* on said arms *d''* having notches *h'* therein; pins *h'* on said cross-pieces *d'* adapted to rest against said cams; side rails D for said sections A; a bottom 120 consisting of a front section B and a rear section B'; hinges F secured to the rear side rail D; cross-pieces *f* for said rear bottom section, slidably secured to the free leaves of said hinges; all coacting for the purpose specified. 125

8. In a structure of the class described, the combination of the end sections A A and A' A'; abutting top rails *a* and *a'* therefor; slotted

tongues j' projecting from said rail a into said rails a' ; suitable pivot-pins j' engaging said slots; bottom cross rails or pieces d' for said sections A'; rearwardly-projecting arms d'' on 5 said sections A; upwardly-projecting pins a on said arms d'' ; slots g' in said cross-pieces d' engaging said pins; side rails D for said sections A; a bottom consisting of a front section B and a rear section B'; hinges F secured 10 to the rear side rail D; cross-pieces f for said rear bottom section, slidably secured to the free leaves of said hinges, all coacting for the purpose specified.

9. In a structure of the class described, the 15 combination of the end sections A and A'; abutting top rails a and a' therefor; slotted tongues projecting from said rails a into said rails a' ; suitable pivot-pins engaging said slots; rearwardly-projecting arms or hinge members on 20 said sections A, having upwardly-projecting pins thereon; forwardly-projecting hinge members on said sections A' having slots therein engaging said pins; cams on said rearwardly-projecting arms or hinge members, having 25 notches therein; pins on said rear hinge member, adapted to rest against said cams; links pivotally secured to said rearwardly-projecting hinge member having slots therein; suitable pins on said forwardly-projecting hinge 30 member engaging said slots; a bottom consisting of front and rear sections; a hinge carried by said front section; and a sliding connection for said rear bottom section to said hinge, all coacting for the purpose specified.

35 10. In a structure of the class described, the combination of the end sections A and A'; abutting top rails a and a' therefor; slotted tongues projecting from said rails a into said rails a' ; suitable pivot-pins engaging said slots; rearwardly-projecting arms or hinge members on 40 said sections A, having upwardly-projecting pins thereon; forwardly-projecting hinge members on said sections A', having slots therein engaging said pins; cams on said rearwardly-projecting arms or hinge members; pins on said rear hinge member, adapted to rest against said cams; links pivotally secured to said rearwardly-projecting hinge member having slots therein; suitable pins on said forwardly-projecting hinge 45 member engaging said slots; a bottom consisting of front and rear sections; a hinge carried by said front section; and a sliding connection for said rear bottom section to said hinge, all coacting for the purpose specified.

55 11. In a structure of the class described, the combination of the end sections A and A'; abutting top rails a and a' therefor; slotted tongues projecting from said rails a into said rails a' ; 60 suitable pivot-pins engaging said slots; rearwardly-projecting arms or hinge members on said sections A; having upwardly-projecting pins thereon; forwardly-projecting hinge members on said sections A' having slots there-

in engaging said pins; links pivotally secured 65 to said rearwardly-projecting hinge members having slots therein; suitable pins on said forwardly-projecting hinge members engaging said slots; a bottom consisting of front and rear sections; a hinge carried by said front 70 section; and a sliding connection for said rear bottom section to said hinge, all coacting for the purpose specified.

12. In a structure of the class described, the combination of the end sections A and A'; abutting 75 top rails a and a' therefor; slotted tongues projecting from said rails a into said rails a' ; suitable pivot-pins engaging said slots; rearwardly-projecting arms or hinge members on 80 said sections A, having upwardly-projecting pins thereon; forwardly-projecting hinge members on said sections A', having slots therein engaging said pins; cams on said rearwardly-projecting arms or hinge members; pins on 85 said rear hinge member adapted to rest against said cams; a bottom consisting of front and rear sections; a hinge carried by said front section; and a sliding connection for said rear bottom section to said hinge, all coacting for the purpose specified.

90 13. In a structure of the class described, the combination of the end sections A and A'; abutting top rails a and a' therefor; slotted tongues projecting from said rails a into said rails a' ; suitable pivot-pins engaging said slots; rearwardly-projecting arms or hinge members on 95 said sections A, having upwardly-projecting pins thereon; forwardly-projecting hinge members on said sections A' having slots therein engaging said pins; a bottom consisting of front and rear sections; a hinge carried by said front section; and a sliding connection for said rear bottom section to said hinge, all coacting for the purpose specified.

100 14. In a structure of the class described, the combination of the end sections A and A'; abutting top rails a and a' therefor; slotted tongues projecting from said rails a into said rails a' ; suitable pivot-pins engaging said slots; rearwardly-projecting arms or hinge members on 105 said sections A, having upwardly-projecting pins thereon; forwardly-projecting hinge members on said sections A' having slots therein engaging said pins; cams on said rearwardly-projecting arms or hinge members; pins on 110 said rear hinge member, adapted to rest against said cams; links pivotally secured to said rearwardly-projecting hinge member having slots therein; suitable pins on said forwardly-projecting hinge member engaging said slots; a bottom consisting of front and rear sections; and suitable hinge connections therefor, all coacting for the purpose specified.

115 15. In a structure of the class described, the combination of the end sections A and A'; abutting top rails a and a' therefor; slotted tongues projecting from said rails a into said rails a' ; suitable pivot-pins engaging said slots; rear-

wardly-projecting arms or hinge members on said sections A, having upwardly-projecting pins thereon; forwardly - projecting hinge members on said sections A' having slots there-
5 in engaging said pins; links pivotally secured to said rearwardly-projecting hinge member having slots therein; suitable pins on said forwardly-projecting hinge member engaging said slots; a bottom consisting of front and
10 rear sections, and suitable hinge connections therefor, all coacting for the purpose specified.

16. In a structure of the class described, the combination of the end sections A and A'; abutting top rails *a* and *a'* therefor; slotted tongues projecting from said rails *a* into said rails *a'*; suitable pivot-pins engaging said slots; rearwardly-projecting arms or hinge members on said sections A, having upwardly-projecting pins thereon; forwardly - projecting hinge members on said sections A' having slots there-
20 in engaging said pins; cams on said rearwardly-projecting arms or hinge members, having notches thereon; pins on said rear hinge mem-
25 ber adapted to rest against said cams; a bottom consisting of front and rear sections, and suitable hinge connections therefor, all coacting for the purpose specified.

17. In a structure of the class described, the combination of the end sections A and A'; abutting top rails *a* and *a'* therefor; slotted tongues projecting from said rails *a* into said rails *a'*; suitable pivot-pins engaging said slots; rearwardly-projecting arms or hinge members on
35 said sections A, having upwardly-projecting pins thereon; forwardly - projecting hinge members on said sections A' having slots there-
in engaging said pins; cams on said rearwardly-projecting arms or hinge members; pins on
40 said rear hinge member, adapted to rest against said cams; a bottom consisting of front and rear sections, and suitable hinge connections therefor, all coacting for the purpose specified.

45 18. In a structure of the class described, the combination of the end sections A and A'; abutting top rails *a* and *a'* therefor; slotted tongues projecting from said rails *a* into said rails *a'*; suitable pivot-pins engaging said slots; rear-
50 wardly-projecting arms or hinge members on said sections A, having upwardly-projecting pins thereon; forwardly - projecting hinge members on said sections A' having slots there-
in engaging said pins; a bottom consisting of front and rear sections, and suitable hinge connections therefor, all coacting for the purpose specified.

55 19. In a structure of the class described, the combination of the end portions formed in sec-
tions; a hinge connection therefor, consisting of a hinge having a pivot-pin and a cam bearing thereon; an opposite member slotted to engage said pivot-pin; a pivoted link on one of said hinge members having a slot therein;

a pin on the opposite member engaging said 65 slot; a bottom consisting of front and rear sections; a hinge, one leaf of which is secured to said front section; a sliding connection for the rear section to the free leaf of said hinge; a link, having a slot therein, pivoted to one of 70 said sections; and a pin on the other section engaging said slot, for the purpose specified.

20. In a structure of the class described, the combination of the end portions formed in sections; a hinge connection therefor consisting 75 of a hinge having a pivot-pin and a cam bearing thereon; an opposite member slotted to engage said pivot-pin; a bottom consisting of front and rear sections; a hinge, one leaf of which is secured to said front section; a sliding connection for the rear section to the free leaf of said hinge; a link, having a slot therein, pivoted to one of 80 said sections; and a pin on the other section engaging said slot, for the purpose specified. 85

21. In a structure of the class described, the combination of the end portions formed in sections; a hinge connection therefor consisting of a hinge having a pivot-pin and a cam bearing thereon; an opposite member slotted to 90 engage said pivot-pin; a pivoted link on one of said hinge members having a slot therein; a pin on the opposite member engaging said slot; a bottom consisting of front and rear sections; a hinge, one leaf of which is secured 95 to said front section; a sliding connection for the rear section to the free leaf of said hinge, for the purpose specified.

22. In a structure of the class described, the combination of the end portions formed in sections; a hinge connection therefor consisting of a hinge having a pivot-pin and a cam bearing thereon; an opposite member slotted to engage said pivot-pin; a bottom consisting of front and rear sections; a hinge, one leaf of which is secured to said front section; and a sliding connection for the rear section to the free leaf of said hinge, for the purpose specified. 100 105

23. In a structure of the class described, the combination of the end portions formed in sections; suitable hinge connections therefor; a bottom consisting of front and rear sections; a hinge, one leaf of which is secured to said front section; a sliding connection for said 110 rear section to the free leaf of said hinge; a link having a slot therein pivoted to one of said sections; and a pin on the other section engaging said slot, for the purpose specified. 115

24. In a structure of the class described, the combination of the end portions formed in sections; suitable hinge connections therefor; a bottom consisting of front and rear sections; a hinge, one leaf of which is secured to said front section; a sliding connection for said 120 rear section to the free leaf of said hinge, for the purpose specified. 125

25. In a structure of the class described, the

combination of the end portions formed in sections; a hinge connection therefor consisting of a hinge member having a pivot-pin and a cam bearing thereon; an opposite member slotted to engage said pivot-pin; a pivoted link having a slot therein on one of said hinge members; a pin on the opposite member engaging the said slot; a bottom consisting of front and rear sections, and suitable hinge connections therefor, for the purpose specified.

26. In a structure of the class described, the combination of the end portions formed in sec-

tions; a hinge connection therefor consisting of a hinge member having a pivot-pin and a cam bearing thereon; an opposite member slotted to engage said pivot-pin; a bottom consisting of front and rear sections; and suitable hinge connections therefor, for the purpose specified.

20 In witness whereof I have hereunto set my hand in the presence of two witnesses.

LEWIS H. BULLARD.
